(57) **CLAIM**

The ornamental design for a bulkhead for an aircraft, as shown and described.

DESCRIPTION

FIG. 1 is a front perspective view of a bulkhead for an aircraft showing our new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines illustrate portions of the bulkhead for an aircraft that form no part of the claimed design.
